UNITED STATES PATENT OFFICE

123,966

DESIGN FOR A REFUSE TRUCK

Robert D. Woodcock, Rockville Centre, N. Y.

Application July 21, 1939, Serial No. 86,170

Term of patent 14 years

To all whom it may concern:

Be it known that I, Robert D. Woodcock, a citizen of the United States, residing in Rockville Centre, in the county of Nassau, State of New York, have invented a new, original, and ornamental Design for a Refuse Truck, of which the following is a specification, reference being had to the accompanying drawings, forming a part thereof, wherein:

Fig. 1 is a view in side elevation of the new design of the refuse truck;

Fig. 2 is a view in rear elevation of the same.

Fig. 3 discloses a top plan view of the refuse truck.

The side of the refuse truck opposite to that shown in Fig. 1 is substantially identical therewith.

The characteristic features of my design reside in the portions shown in solid black lines in the drawing.

I claim:

The ornamental design for a refuse truck, as shown, and described.

ROBERT D. WOODCOCK.
